UNITED STATES PATENT OFFICE.

DANIEL DOCKSTADER, OF FONDA, NEW YORK.

ELEVATOR AND CARRIER.

SPECIFICATION forming part of Letters Patent No. 244,563, dated July 19, 1881.

Application filed March 15, 1881. (No model.)

To all whom it may concern:

Be it known that I, DANIEL DOCKSTADER, of Fonda, in the county of Montgomery and State of New York, have invented a new and Improved Elevator and Carrier, of which the following is a specification.

The object of this invention is to provide a simple, strong, and durable hay elevator and carrier.

10 The invention consists of novel devices for holding the carrier in place while loading, for unlocking the carrier so that it may be moved on its track, all of which will be hereinafter described.

15 Figure 1 is a sectional side elevation of the device. Fig. 2 is an end vertical section on line $x-x$, Fig. 1.

Similar letters of reference indicate corresponding parts.

20 In the drawings, A represents the carrier-frame suspended from a track, B, by means of straps and wheels C C', respectively, the straps C being secured on opposite sides of the frame A and extended upward, and having their ends turned over at right angles and having pivoted in them the wheels C', that rest upon the track B. Said track B is designed to be suspended from the rafters of the building by suitable rods D.

30 In the under face of the track B is a longitudinal socket, a, in which is pivoted a catch, E, lying lengthwise with said socket a, whose purpose will be hereinafter set forth.

Within the carrier-frame A a sheave, G, that revolves in a vertical plane, is set on a transverse shaft, G', and placed higher up in frame A, and a short distance to the left, as shown in Fig. 1, a dog, H, is pivoted on a transverse rod, H', in such a position that the 35 point of said dog H shall reach to the periphery of the said sheave G and serve to stop the elevating-rope K at the proper point, as will be described.

The elevating-rope K has one end made fast 40 to a staple, c, fixed in the end of the frame A, while its other end is passed over the said sheave G and out of an orifice, g', in the end of said frame A.

A sliding block, I, provided with a vertical

slot, d, extending through it, is suspended in 50 frame A, on a transverse rod, I', that passes through the frame A from side to side thereof, so that the enlarged head of said block I hangs below the said carrier-frame A.

On the right of the rope K is a pulley-block 55 and hook, L, and on said rope K is rigidly secured a ring, f, of leather, metal, or other substance, against which the point of the dog H is to engage.

When the parts are in place, as shown in 60 Fig. 1, the carrier is in position for loading, the hooked end of the catch E being entered in the orifice g, made in the rear end of the frame A, and thereby holding said frame A fixed. When the hay-fork, (not shown,) which 65 is designed to be connected with the block and hook L, is loaded, the rope K is drawn in the direction of the arrow, Fig. 1, and the block L thereby drawn upward in contact with the sliding block I, and forces said block 70 I up against the catch E, thereby raising the latter so that it can pass out of the orifice g. Thus the carrier A is free to move and the load suspended from the block, and hook L is held at suitable elevation, the rope K being 75 prevented from being drawn back by the engagement of the point of the dog H upon the rope K, just in rear of the stop or ring f, which by this time has arrived at the top of the sheave G. When the load is removed the 80 carrier A may be moved back again for another load, and the hooked end of the catch E, entering the orifice g, passes over the short end of the dog H, and, pressing said short end down, thereby disengages the point of 85 said dog H from the stop or ring f, and thus permits the block and hook L to descend for another load, said hooked end of the catch E, on being disengaged from the dog H, at once engaging on the inner side of the orifice g, and 90 thereby holding the frame A in a fixed position until another load is elevated.

Having thus fully described my invention, I claim as new and desire to secure by Letters Patent—

1. An elevator and carrier constructed substantially as herein shown and described, consisting of suspended frame A, containing

sheave G, dog H, and sliding block I, arranged and operated as set forth.

2. The combination, with the frame A, having orifice g, and track B, having socket a, of 5 the hooked catch E, substantially as herein shown and described, whereby the carrier is held fixed, as set forth.

3. In an elevator and carrier, as a means

for releasing the same from a fixed position, the sliding block I, substantially as herein 10 shown and described.

DANIEL DOCKSTADER.
